ELECTRIC SWITCH

James P. Dunlap, Chicago, Ill., assignor to Royal
Electric Manufacturing Company, Chicago, Ill.,
a corporation of Illinois

Application April 24, 1941, Serial No. 390,062

16 Claims. (Cl. 200—48)

This invention relates to electric switches and more particularly to switches of the type used in the transmission and distribution of power, especially switches of medium and high current carrying capacities. The principles of the present invention are particularly concerned with the construction of air break disconnecting switches wherein the switch blades and contacts are exposed to atmosphere and therefore subject to corrosion and also frequently exposed to rain, sleet, and the like.

An electric switch of the type here involved includes one or two movable parts adapted to be brought into and out of engagement with one another to open or close a line circuit or a portion of a line circuit. The switch includes a terminal for each switch member, which terminals are permanently connected to a line or the like and are also connected to the associated movable switch part, that is, the movable switch blade or movable switch contact, as the case may be. The use of flexible conductors for maintaining the circuit connection with a movable switch contact is objectionable. Such contacts must necessarily be of rather fine wire. Any corrosion of the fine wire results in a substantial decrease in the effective cross sectional area of the remaining copper. Furthermore, the conductor is subjected to flexing during each switch closing and switch opening operation. This alternate flexing produces a hardening of the braided copper and therefore renders it more susceptible to breakage.

It is one of the objects of the present invention to eliminate the need of a braided copper or other flexible connection between the movable switch member and its associated terminal. This is accomplished, in one embodiment of the present invention, by mounting the movable switch member on a hinge or the like which makes a wiping pressure contact with a stationary stud or the like. In the preferred embodiment of the present invention the switch contact comprises one or more flexible rods or wires freely flexible at their contact making end and supported at a point spaced from the contact making end. The wires may consist of copper weld tubes, that is, a copper tube welded on a steel filling core. The wires may be clamped intermediate their ends so that both ends of the wires may be flexed out of their normal position. One end of each copper weld wire is contacted by the switch blade. The other end of each copper weld wire slides on and is flexed by a stationary contact stud which is connected to or

forms a part of the switch terminal and thus establishes circuit connections to the copper wire.

In one embodiment of the present invention the switch contact is pivotally mounted and is moved by the switch blade to its alternate positions as the switch blade moves to open the switch circuit or to close the switch circuit. Since the switch blade constitutes the only means for moving the switch contact, the switch contact should remain in its switch open position, once it is moved to that position, until the blade is again actuated to close the switch. It is one of the objects of the present invention to provide positive means for maintaining the switch contact in its open position as required. This is accomplished, in one embodiment of the present invention, by utilizing the springiness of the switch contact wire. The contact stud engaged by the contact wire is of a non-circular shape, so shaped that as the wire reaches its full open position a part of the stress on the wire is released. Any initial movement of the spring wire towards its switch closed position must result first in an increase in the spring stress on the wire. This effectively prevents movement of the switch contact wires from their open towards their closed position by vibration, wind forces, gravity, or the like. In lieu of this, or in conjunction with it, means may be provided for forming a snap lock to hold the contact in its open position.

It is a further object of the present invention to provide improved means for counterbalancing the switch blade in a switch wherein the blade moves vertically.

The attainment of the above and further objects of the present invention will be apparent from the following specification taken in conjunction with the accompanying drawings, forming a part thereof.

In the drawings:

Figure 1 is a side elevation of a vertical break type of outdoor disconnecting switch embodying the present invention;

Figure 2 is a plan view of the switch of Figure 1 with part of the structure broken away to illustrate the underlying parts;

Figure 3 is a sectional view taken along the line 3—3 of Figure 1;

Figure 4 is an enlarged sectional view of the switch contact taken along the line 4—4 of Figure 1;

Figure 5 is a sectional view taken along the line 5—5 of Figure 4;

Figure 6 is an enlarged fragmentary view of a portion of Figure 5;

Figure 7 is a sectional view taken along the line 7—7 of Figure 5;

Figure 8 is a plan view of a switch illustrating another embodiment of the present invention;

Figure 9 is a side elevational view of the upper part of the switch of Figure 8;

Figure 10 is a view taken along the line 10—10 of Figure 11;

Figure 11 is a sectional view taken along the line 11—11 of Figure 10;

Figure 12 is a perspective view of the contact carriage of the switch of Figure 8;

Figure 13 is a sectional view taken along the line 13—13 of Figure 11;

Figures 14 and 15 are views corresponding to Figures 10 and 11 and illustrating a modified construction;

Figure 16 is a perspective view of the locking cam of the switch of Figures 14 and 15;

Figure 17 is a side view of the upper portion of a three insulator switch of the type shown in Figure 1, and illustrating another embodiment of the present invention;

Figure 18 is a sectional view of the contacting mechanism at the hinged end of the blade of Figure 17, said view being taken along the line 18—18 of Figure 19;

Figure 19 is a plan view of the hinged end of the blade and contacting mechanism of the switch of Figure 17; and

Figure 20 is a sectional view taken along the line 20—20 of Figure 19.

Reference may now be had more particularly to the switch illustrated in Figures 1 to 6 inclusive. This switch is an outdoor type vertical break disconnecting switch of a rating of approximately 15,000 volts and six hundred amperes. The switch, indicated in general by the reference numeral 1, includes a channel iron mounting base 2 on which are mounted two stationary insulators 3 and 4 and an axial rotatable insulator 5. The insulators may be mounted on the base in any desired manner. The mounting for the insulator 5 includes a bearing 6. Means is provided for axially rotating the insulator 5 as, for instance, by a crank 7. In a three phase system three switches, such as shown in Figure 1, are mounted side by side, and the cranks 7 of the rotary insulators 5 are interconnected for simultaneous operation. The insulators 4 and 5 include insulator caps 10 and 11 suitably secured to the respective insulators. A bearing stud 12 is bolted or otherwise suitably secured to the insulator cap 11, the axis of the stud being coaxial with the axis of the insulator. A back bearing 13, which is bolted to a supporting bar 14, is slipped over the stud 12 so that the stud can rotate while the supporting bar 14 remains stationary. The stud fits snugly through the bearing 13 so that there is only a slight amount of play between the supporting bar and the bearing. The opposite end of the bar 14 is bolted to a hinge bracket 16 which in turn is bolted to the insulator cap 10. Thus the supporting bar braces the insulators 4—5 while permitting rotation of the insulator 5 with respect to the insulator 4. The supporting bar 14 is made of copper or other material of high current carrying capacity and is of sufficient cross sectional area for the current carrying capacity of the switch. The bar 14 constitutes one terminal of the switch and has a plurality of bolt holes at

one end thereof for receiving a clamp for clamping a line conductor 17 thereto.

An actuating crank 18 is bolted or otherwise suitably secured to the end of the stud 12 so that upon rotation of the insulator 5 the crank 18 is rotated.

The hinge bracket 16 includes a pair of upstanding arms 20—20 having aligned perforations or holes therethrough for receiving a pin 21 which is journalled in the arms 20—20. A switch blade 25 is secured to the pin 21. The switch blade consists of a blade carriage 26 secured to the pin 21, a tube 27, and a contact making cam 28, all of material of high current carrying capacity. The blade carriage 26 has a pair of arms 30—30 integral therewith and terminating at the rear of the blade in split clamps 31—31 that fit between the arms 20—20 of the hinge bracket 16, as may be seen from Figures 2 and 3. The pin 21 is then inserted through aligned holes in the arms 20 and through aligned perforations in the split clamps 31. The clamps are then tightened by then tightening nuts at the ends of bolts 33. This tightly clamps the blade carriage to the pin 21, thus establishing a good electrical connection between the blade carriage and the pin.

Circuit connections from the line 17 to the switch blade are established by way of the supporting bar 14, a contact rod casting 34 and six contact rods 35 which are secured to the casting 34 and press against the pin 21. The contact rods consist of copper clad steel tubes. The copper affords the necessary current capacity and the steel core affords the necessary resiliency. The six rods 35 are press fitted into individual holes in the casting 34 and then secured in place by socket head set screws 36, thus establishing firm electrical and mechanical connections between the casting 34 and the copper jacket on the contact rods 35. The casting 34 is then bolted or otherwise rigidly secured to the supporting bar 14 in firm electrical and mechanical connection therewith. The contact rod casting is of material having high current carrying capacity. The distance between the two rows of rods 35—35 at the casting 34 is slightly less than the diameter of the pin 21. The rods 35 are thus slightly spread apart by the pin 21 and exert a high spring pressure thereagainst. The circumference of the pin 21 is smooth so that upon rotation of the pin 21 the contact rods slide freely on the pin but maintain a high pressure thereagainst, thus maintaining electrical connection between the casting 34 and the pin 21.

The blade carriage 26 has a pair of upstanding ears 40—40 integral therewith. A connection rod 41 is connected to the ears 40—40 by a universal coupling 42. The opposite end of the connecting rod 41 is connected to the crank 18 by another universal coupling 43. Thus upon rotation of the crank 18 the connecting rod rotates the switch blades 35 vertically about the pin 21 as an axis. The switch blade moves from the switch closed position illustrated in full lines in Figure 1 to a switch open position illustrated in fragmentary portion by the dotted lines in Figure 1. It is to be noted that in moving to the switch open position the blade passes through a vertical position and then moves slightly beyond its vertical position. As a result there is no tendency for the blade to fall from its open position to its closed position.

Means is provided for counterbalancing the weight of the switch blade, thus easing the

switch opening and closing operation. This comprises two similar spring housings 46 each of which is bolted to one of the arms 30 of the blade carriage by a pair of bolts 47-47 to be rigid with the blade carriage. Each housing extends over and encloses the part of the pin 21 that projects beyond the arms 20-20 of the hinge bracket 16. A coiled torsion spring 48 surrounds the projecting part of the pin 21 in each spring housing. One end 50 of the spring extends into a small hole in the spring housing 46. The other end 51 of the coiled spring extends into and is secured in a hole in the arm 20 of the hinge bracket 16. The two springs thus counterbalance the weight of the switch blade. Each housing 46 thus protects the springs from the weather and prevents the formation of ice and sleet thereon.

The contact making cam 28 of the switch blade is of a generally hollow rectangular formation and has a shank portion 53 that is press fitted or otherwise firmly secured in the tube 27 in firm electrical and mechanical connection with the tube 27 of the blade. The tube 27 may, for instance, make a shrink fit on the shank portion 53. The contact making cam includes a cam portion 56 which is rounded and of a generally elliptical or oval cross section in vertical section. The cam portion 56 is adapted to be moved into and out of engagement with a contact structure 60 that is pivotally mounted on the insulator 3 and connected to the opposite terminal of the switch.

A description will now be given of the construction of the contact structure 60. The insulator 3 has an insulator cap 62 suitably secured thereto in the usual manner, to which is bolted a contact base and terminal 63. The contact base includes a circular portion 64 for bolting to the insulator cap, from which circular portion there rises an inclined portion 65 terminating in a rectangular bar portion 66, all of which constitutes one rigid casting. The bar portion 66 is the terminal of the switch and is provided with holes for receiving a line conductor which may be clamped or otherwise secured thereto in any desired manner. The bar portion 66 has an upward and forwardly extending portion 67 that terminates in a cam portion 68 having a horizontal pin receiving hole for receiving a pin or stud 70 that swivels a contact rod bracket or carriage 71 to the contact base. The carriage 71 has a pair of arms 72-72 that embrace the portion 67, and have aligned holes therein for receiving the stud 70. The contact rod carriage has a head portion 73 extending above and below the arms 72, as may be seen from Figures 1 and 5. The head 73 has six rod receiving holes therein in two rows of three aligned holes in each row. Upper contact rods 75 and lower contact rods 76 are press fitted through the holes in the head 73. The rods 75-76 consists of steel cores within copper jackets, whereby the copper affords the necessary current carrying capacity and the steel affords the necessary resiliency or springiness. The press fit of the rods in the respective holes in the head 73 assures establishment of a firm electrical and mechanical connection between the rods and the carriage.

The rear ends of the rods embrace the cam portion 68 and are slightly spread apart by the cam portion whereby the springiness of the rods causes the rods to exert a high pressure against the cam portion 68, thus maintaining firm elec-

trical connection with the cam portion. When the contact structure 60 is in the switch closed position as illustrated in full lines in Figures 1 and 5, the contact rods engage the surfaces 78-79 of the cam portion 68. The distance between these surfaces is in excess of the distance between the rows of rods 75-76 so that the cam portions 78-79 spread the rods apart, thus stressing the rods and causing the rods to exert a spring pressure against the surfaces 78-79 to maintain firm electrical connection with those surfaces. When the contact structure is moved to the switch open position in a manner to be more fully set forth as this description proceeds, the rods slide along the surfaces 78-79 and ultimately come into engagement with the surfaces 80 and 81. These surfaces are a distance apart slightly less than the distance between the surfaces 78-79, the difference being sufficient to produce an appreciable relief in the stress on the conducting rods. The conducting rods are then not spread apart at all by the surfaces 80-81. Thus when the carriage is moved to the switch open position, which is the position illustrated in dot-dash lines in Figure 5, the contact rods tend to maintain the carriage 71 in its elevated position, the stiffness of the contact rods preventing the contact rod carriage 71 from moving to the full line position of Figure 4 where the ends of the contact rods would be spread apart by the cam surfaces 78-79.

In the operation of the switch it is essential that once the switch blade has been moved to the open position and has moved the contact structure 60 to the open position, the contact structure must stay in its open position until it is moved to its closed position by the switch blade. There must be no reasonable possibility of the movement of the contact structure to its switch closed position by wind, accompanied by vibrations, or other extraneous causes. Additional means is provided for assuring holding of the contact structure in its switch open position. This additional means comprises a locking cam lug 85 having curved cam surfaces 86-87 a distance apart greater than the distance between the nearest surfaces of the upper end contact rods 88-88. The two outermost rods in the top row of contact rods are longer than the other four rods and extend beyond the cam portion 68 to overlie the locking cam lug 85. When the contact structure is moved to its open position the end contact rods 88-88 are first spread apart horizontally by the curved portions 86-87 of the cam lug 85 and then snapped back into the curved portions 90-90 of the locking cam lug 85, as illustrated in dot-dash lines of Figure 7. These two end rods 88-88 thus serve to hold the contact structure 60 in its switch open position against the action of extraneous forces such as wind, vibration or the like, and yet allow switch closing movement by action of the switch blade, due to the fact that the contact rods are sufficiently resilient to permit spreading of the rods 88-88 to clear the surfaces 86-87.

From Figures 1 and 6 it may be seen that the ends of the contact rods of the contact structure 60 are flared outwardly along smooth curves. This facilitates the switch closing operation.

An explanation will now be given of the mode of operation of the switch thus far described. To open the switch the insulator 3 is rotated axially, thus rotating the crank 18 which causes the con-

necting rod 41 to pull upon the ears 40 of the blade carriage 26 to swing the switch blade from the full line position to the dotted line position of Figure 1. As the switch blade moves upwardly the cam portion 56 forces the contact structure 60 to swing about the pin or stud 70. When the contact structure 60 reaches the position illustrated in dotted lines in Figures 1 and 4 the cam 56 clears the contact rods of the contact structure. The switch blade continues to move towards its full open position while the contact structure 60 remains in the position illustrated in dotted lines in Figures 1 and 5, which is the full open position of the contact structure. When the switch is closed the center line of the contact structure and the center line of the switch blade are in toggle position. This facilitates the switch opening operation, especially if the switch opening operation is to take place when the switch is coated with ice or sleet.

During the switch closing operation the reverse action takes place. The switch blade moves towards its closed position without affecting the contact structure 60 until the cam 56 engages the lower row of contact rods 76. Further movement of the switch blade causes the contact structure to swivel about the pin 70 from the dotted line position to the full line position. The cam 56 exerts a powerful camming action to spread the rows of contact rods 75-76 apart and to scrape away any film of dirt or oxide from the rods at the place of contact whereby a high pressure at clean contact areas is obtained.

It is to be noted that there are no braided or laminated conductors for extending circuit connections to the swinging switch blade or for extending circuit connections to the swinging contact structure 60. Such braided or laminated conductors have been a constant source of trouble because repeated openings and closings of the switch have resulted in breaking or tearing of the laminations. In the switch of the present construction all circuit connections between relatively movable parts are maintained by sliding connecting fits. This permits the camming action of the switch blade at the contact structure 60 on the initial switch opening operation, with a resulting powerful ice breaking action, without at the same time encountering the disadvantages inherent in the use of flexible braided conductors between the line and the associated pivoted contact member or contact making member. Furthermore, the spring housings 46 protect the counterbalancing springs from ice and sleet formation which would otherwise interfere with the switch opening operation.

The switch is provided with arcing horns as is usual. To this effect a copper clad rod 94 is pressed into a hole in the bar 66 and secured in place by a pair of set screws. A cooperating rod 95 is secured to the switch blade 25. The rod 95 slides on the rod 94 during switch opening operation and slides out of contact therewith after the cam 56 has separated from the contact structure 60.

Reference may now be had more particularly to the switch illustrated in Figures 8 and 9. This switch is of the double break type and includes two contacts mounted on stationary insulators and adapted to be bridged by a switch blade mounted on an axially rotatable insulator located centrally between the two stationary insulators. The three insulators of this switch are indicated at 100, 101 and 102, of which the 75

insulators 100 and 102 are stationary and the insulator 101 axially rotatable. The three insulators are mounted upon a supporting base in any desired manner as, for instance, in the same manner as are the stationary insulators and the rotary insulator of the switch of Figure 1. The insulators 100 and 102, and the respective contacts associated therewith, are of identical construction. A description of one will therefore suffice also for the other. Each insulator 100-102 has an insulator cap 103 suitably secured thereto. A contact support 105 having a circular portion 106 is bolted at its circular portion to the insulator cap 103. The contact support includes a line terminal bar portion 107 having an upraised circular part 108 from which extends centrally a stud or shank 109. A contact rod carriage 111 is mounted to rotate about the shank 109. This carriage includes upper and lower arms 112-113 having holes 114 and 115 therein of different sizes but centered on the same axis. The arm 113 is slipped over the shank 109 until the upraised circular portion 108 enters the hole 115. At that time the upper arm 112 rests upon the top flat surface 117 of the shank 109, and a short stud portion 118 of the shank enters into the hole 114. The contact rod carriage 111 is thus pivoted about the shank 109. A short bolt 120 threads into the shank 109 and holds the contact rod carriage 111 against upward movement without preventing rotation of the contact rod carriage. At its forward end the contact rod carriage or bracket 111 includes a block 122 integral with the arms 112-113 and having a bolt receiving hole 123 extending therethrough. Contact fingers 125-125 are bolted to the opposite surfaces of the block 122 by a bolt 126. The contact fingers 125-125 serve to clamp four copper weld contact rods 128-128 and 129-129. The copper weld rods 128-129 are of the same construction as are the rods 88 or 35 of the switch of Figure 1. They are clamped into firm mechanical and electrical contact with the block 122 by the fingers. The forward ends of the rods 128-129 are outwardly flared, as is apparent from Figures 8 and 10, and the rods 129 are slightly longer than are the rods 128. The opposite ends of the rods 128-129 embrace the shank 109 and are bowed away from one another slightly by the shank whereby the rods exert a firm pressure against the shank. The carriage 111 and contact support 105 including the shank 109 are made of material of high current carrying capacity. As a result the shank 109 extends the circuit from a line terminal bar portion 107 to the contact rods 128-129.

A tubular switch blade 133 is rigidly secured to the top of the insulator cap on the insulator 101 in any desired manner as, for instance, by being clamped thereto. To each end of the tubular blade 133 there is secured a cam type contact making structure 134. The contact making structure 134 has a shank 136 that makes a snug fit within the tube of the blade 133, as illustrated in Figures 10 and 11. A firm mechanical and electrical connection may be obtained between the tube 133 and the shank 136 in any desired manner as, for instance, by shrinking the tube 133 onto the shank 136. At one end the contact making member includes a contacting cam 138 which extends between the rods 128-129 and spreads them slightly. As a result the rods exert a high pressure against the cam 138 and thus maintain good electrical connection between the contact rods and the contact making cam 138.

The contact making structure 134, including cam 138, is made of material of high current carrying capacity suitable for switch use.

To open the switch illustrated in Figure 8 the insulator 101 is rotated in a clockwise direction, thus rotating the switch blade 133 in the same direction. The cam 138 forces the contact rods 128 and the associated contact rod carriage 111 to turn about the shank 109 as a center. This action continues until the contact rod carriage 111 and the rods 128-129 reach the position illustrated in dotted lines in Figure 8. At that point the cam clears the contact rods 128-129 and the continued movement of the switch blade 133 towards its open position results in separation of the blade from the contact structure including the rods 128-129.

During the time the switch blade is in its open position the contact rod carriage 111 should remain in its open position as illustrated in dotted lines in Figure 8. To assure this the shank 109 is of a star shape in cross section, as illustrated in Figure 10. The contact rods 128-129 engage the shank surfaces 140-144 when the switch is closed. These surfaces are a distance apart slightly in excess of the minimum distance between the back ends of the contact rods 128-129. When the switch is open and the contact rods 128-129 are in the dotted line position, illustrated in Figure 10, the contact rods 128 extend between the surface 140 and a surface 145, whereas the contact rods 129 extend between the surface 144 and a surface 146. The rods are now a distance apart slightly less than the distance between the surfaces 140-144. As a result, if an attempt is made to move the contact rod carriage 111 from its dotted line switch open position to its full line switch closed position, it is necessary to force the contact rods apart slightly at the surfaces 140-144, against their natural resiliency. This requires an appreciable force. Therefore, there is no tendency for the contact rod carriage to shift from its open position to its closed position under the action of wind or vibration.

To close the switch the insulator 101 is rotated in a counter-clockwise direction. When the cam 138 rotates beyond its point of engagement with the contact rods 129 it forces the contact rods and the contact rod carriage 111 to swing about the shank 109, and at the same time it cams itself into position between the contact rods 128 and 129 and slightly separates the contact rods. As a result the contact rods exert a very high pressure against the cam 138. Furthermore, during the sliding action of the cam 138 on the rods 128-129 the cam wipes away any dirt or oxide film from the points of contact between the cam and the respective contact rods. There is thus obtained a clean, high pressure, point to point contact between the switch blade and the contact rods. When the switch is closed the circuit extends from the line at one of the bar portions 107, through the shank 109, to the contacting rods 128-129, thence to the cam 138 of the switch blade, and through the switch blade to the contact structure on the opposite stationary insulator, thence to the line terminal of said opposite stationary insulator.

Reference may now be had more particularly to the switch contact structure of Figures 14 and 15. This contact structure is adapted for use on a switch of the type shown in Figures 8 and 9 but is of a larger current carrying capacity. In this instance there are six contact rods 128 and six

contact rods 129 instead of two of each as in the switch of Figures 10 and 11. The shank 109' is a cylindrical shank, two sides of which are milled flat, as indicated at 150-151. When the contact rod carriage 111', which corresponds to the contact rod carriage 111 of the switch of Figure 8, is in its switch closed position the rods 128-129 are slightly spread apart by the shank 109' and exert a high pressure thereagainst. When the carriage reaches its open position, indicated in dotted lines in Figure 11, the rods 128-129 are permitted to come closer together against the milled surfaces 150-151. This serves to hold the contact rod carriage in its switch open position. In addition, the lowermost contact rod in the row 128 is elongated at its rear, as indicated at 153. The elongated portion 153 cooperates with a locking cam 154 of a construction such as is illustrated in Figure 16, for yieldingly holding the carriage 111' in the switch open position. The locking cam 154 is bolted or otherwise rigidly secured to the bar 107 and includes a finger 155 having a cam surface 156. As the carriage 111' swings from its switch closed position to its open position the rod 153 rides up on the surface 156, the rod flexing upwardly under the action of the cam surface 156. As the carriage reaches its full open position the end 153 of the contact rod snaps into a circular depression 157 in the locking cam 154, thus resiliently locking the contact rod carriage in its open position. If an appreciable pressure is exerted against the lowermost rod 128 tending to turn the carriage 111' from its switch open position to its switch closed position, the end portion 153 of the lowermost rod will flex upwardly to ride over the cam surface 154 to free the carriage for rotation towards its closed position.

The switch blade 133' of the switch of Figure 14 has a contact making structure 134' similar to that of the switch of Figure 1, secured thereto in the same manner as was previously described in connection with the switch of Figure 1. The contact making portion 134' includes a cam 138' which enters between the contact rods 128-129 and spreads them apart slightly, against their natural resiliency, and thus maintains a firm pressure engagement between the contact rods and the cam portion 138' of the switch blade. Thus during the switch closing movement the cam exerts a powerful force upon the contact rods, so that only a very slight flexing is necessary in order to obtain the requisite pressure between the contact rods and the cam portion 138'.

Reference may now be had more particularly to Figures 17 through 20, illustrating still another embodiment of the present invention. Insofar as this switch is the same as the switch of Figure 1 similar reference numerals have been used. This switch embodies a different type of contacting mechanism at the hinged end of the blade, which contacting mechanism is particularly useful for switches of very high current carrying capacity, say, 1200 amperes and upwards. The switch includes two stationary insulators 3 and 4 and an axially rotatable insulator 5, all mounted on a base in the same manner as is the switch of Figure 1. The contacting structure on the cap of the insulator 3 is substantially the same as that of the switch of Figure 1, differing therefrom essentially in that a larger number of contact making wires are used. Insofar as the structures are the same, similar reference numerals designate similar parts.

In the switch of Figure 17 the arcing horns have been omitted merely to simplify the illustration, it being understood that the arcing horns may be used if desired. A blade hinge bracket 170 is bolted or otherwise suitably secured to the cap of the insulator 4 and includes a pair of arms 171-171 curved at their upper ends, as indicated at 172, for receiving a pivot pin 173. This pivot pin 173 passes through the arms 171 of the bracket and through a pair of arms 175-175 of a blade supporting carriage 176 in which a tube 27 is inserted to constitute the switch blade 25'. The blade carriage 176 has a pair of upstanding arms 48' that are connected by a connecting rod 41 and universal couplings 42-43 to the crank 18 that is rotated by the insulator 5 to actuate the switch blade in the same manner as was previously described in connection with the switch of Figure 1.

The arms 175-175 of the blade supporting carriage are joined by a cam bar 178 which is an integral part of the casting constituting the blade supporting carriage 176. A pair of spring seats 179 are mounted on the pin 173 between the arms 171-171 and support a counterbalancing spring 180. One end of the spring passes through a hole 181 in the web of the blade hinge bracket 170. The other end of the spring passes under a pin 182 that extends from one of the arms 175 of the blade supporting carriage. The spring thus constantly forces the blade carriage upwardly to counterbalance the weight of the carriage.

The stationary insulator 4 and the rotary insulator 5 are secured together by a bar 14' that is bolted to the blade hinge bracket 170 and in which the pin at the upper end of the cap of the rotary insulator 5 is journaled, as in Figure 1. The bar 14' is made of material of high conductivity and receives the line terminals 17'. A hinged contact block casing 34' of material of high conductivity is bolted or otherwise rigidly secured to the bar 14' in firm mechanical and electrical contact therewith. The casting 34' includes a cam portion 184 that is embraced by the arms 17' of a carriage 11'. The carriage 11' is of a construction substantially identical with the construction of the carriage 11, differing therefrom essentially in that it is of greater width to support a larger number of contact making wires in each of the two rows. The carriage 11' is hinged to the cam portion 184 and secured in place by a pair of bolts to permit oscillation of the carriage 11' about the center 185. The carriage 11' supports two rows of contact wires each row of which contains, in this instance, seven wires. The two rows are indicated at 186 and 187, respectively, so that the wires exert a firm spring pressure against the two cams. A circuit is thus established from the line terminal, through the bar 14' and casting 34', through the rows of wires 186 and 187, to the cam bar 178 of the switch blade and thus to the switch blade.

When the blade is actuated to open the switch the blade carriage swings about the pin 173 as a center to its open position. As the cam bar 178 swings downwardly it first releases the pressure of the cam bar on the rods or wires 186-187, swinging the carriage 11' with it. The carriage 11', of course, swings about the center 185 of the cam 184 as a center. The initial pressure of the rods 186-187 on the cam bar 178 is released after a small amount of turning of the switch blade. Thereafter the wires exert no ap-

preciable pressure on the cam bar 178 thus easing the switch blade opening movement. It is to be noted that during the initiation of the switch blade opening movement the crank 18 and the connecting rod 41 are in a position substantially in toggle, as may be seen from Figure 2. Thus at that time the crank exerts a very powerful force on the switch blade and there is no great difficulty in overcoming the frictional resistance between the rods 186-187 and the cam bar 178. Thereafter, as the crank 18 moves out of position of toggle with the connecting rod 41, the wires exert no appreciable pressure upon the switch blade.

The carriage 11' will be held in its lowermost position by gravity. When the switch blade is actuated to close the switch the cam bar 178 enters between the rods 186-187 and swings them to the position illustrated in Figure 18. If the rods, or the cam 178, have become coated with ice or sleet the cam 178 will break through ice as it forces the contact rods 186-187 apart when the switch blade approaches its full closed position. The cam 184 is also constructed so as to release the pressure on the rods 186-187 when the carriage 11' makes its initial movement towards its switch open position. This will also result in breaking away any ice or sleet that may have formed on the cam 184, or the rods 186-187, during the switch open period because the bars are flexed apart shortly before they reach their full switch closed position. The flexure of the rods or wires 186-187 will result in cracking and breaking of any ice that may have formed thereon at the ends thereof.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. An electric switch including a contact member including a spring contact rod pivotally mounted and having a switch open position and a switch closed position, a contact making member movable into and out of engagement with the contact rod and moving the contact rod to its alternate positions, said members being in a position of toggle when the switch is closed and said contact being swung through a substantial angle by the switch opening movement of the contact making member, and means engaging said rod for resiliently holding the contact member in its switch open position while the two members are out of engagement with one another.

2. In an electric switch having a pivoted switch blade, means for establishing electrical connection between the switch blade and a switch terminal, said means comprising a terminal stud stationary with respect to the terminal, a contact rod bracket mechanically separate from the blade and pivotally mounted to swing about an axis parallel to the pivot axis of the blade, a contact rod secured to the bracket and slidably engaging the stud and exerting a spring pressure thereagainst, said contact rod extending beyond the bracket and slidably engaging the blade, said bracket being moved from a switch closed position to a switch open position by the contact rod as the blade moves to its alternate positions and presses the rod to its alternate positions.

3. In an electric switch having a pivoted switch

blade, means for establishing electrical connection between the switch blade and a switch terminal, said means comprising a terminal stud stationary with respect to the terminal, a contact rod bracket mechanically separate from the blade and pivotally mounted to swing about an axis parallel to the pivot axis of the blade, a contact rod secured to the bracket and slidably engaging the stud and exerting a spring pressure thereagainst, said contact rod extending beyond the bracket, the blade being movable into and out of engagement with the rod, said bracket being moved from a switch closed position to a switch open position by the contact rod as the blade moves to its alternate positions and presses the rod to its alternate positions, and positive means for holding the bracket in its switch open position to which it is moved by the blade.

4. In an electric switch having a pivoted switch blade, means for establishing electrical connection between the switch blade and a switch terminal, said means comprising a terminal stud stationary with respect to the terminal, a contact rod bracket mechanically separate from the blade and pivotally mounted to swing about an axis parallel to the pivot axis of the blade, a contact rod secured to the bracket and slidably engaging the stud and exerting a spring pressure thereagainst, said contact rod extending beyond the bracket, the blade being movable into and out of engagement with the rod, said bracket being moved from a switch closed position to a switch open position by the contact rod as the blade moves to its alternate positions and presses the rod to its alternate positions, and snap locking means engaging the rod in its switch open position and holding the carriage against movement to its switch closed position.

5. An electric switch contact including a pivoted contact rod carriage, a plurality of spring contact rods secured to the carriage with their axes at substantially right angles to the pivot axis of the carriage, each rod being free of the carriage at the two ends of the rod, a stud slidably engaged by one end of each rod as the carriage pivots about its axis, and means cooperating with at least one of the rods for holding the rod and through the rod holding the carriage in the switch open position.

6. In an electric switch, a contact stud, a rod carriage pivoted on the stud, a plurality of contact making rods mounted on said carriage intermediate their ends, a contact making member movable in engagement with the rods on one side of the carriage and pressing said rods towards the switch closed position and by the pressure exerted through the rods, swinging the carriage about the stud from a switch open to a switch closed position, the portions of the rods on the opposite side of the carriage making sliding pressure engagement with the stud for extending the circuit connection from the stud to the contact making member.

7. In an electric switch, a switch blade mounted for swinging movement at one end and having a contact making member at the opposite end, a curved conducting cam constituting a rigid part of the blade adjacent the mounted end thereof, and a plurality of conducting rods of spring material pressing against said curved conducting cam and making a sliding fit therewith for maintaining circuit connections to the blade, said cam exerting a camming action on the rods as the blade is swung from its switch open position to its switch closed position.

8. An electric switch including a mounting bracket having a pair of arms, a blade carriage having a pair of arms extending between the arms of the bracket, a pivot pin rigid with the blade carriage and extending through and rotatable in the bracket arms and constituting a pivot support for the blade carriage, the pivot pin being of material of high electric conductivity, spring conducting rods pressing against said pin between the bracket arms, said pin sliding with respect to the rods as the blade carriage pivots between the arms of the mounting carriage for maintaining electric circuit connections with the carriage, separate spring housings secured to each carriage arm, the housings closely embracing the bracket arms, and blade counterbalancing springs in said housings.

9. An electric switch including a mounting bracket having a pair of arms, a blade carriage having a pair of arms extending between the arms of the bracket, a pivot pin extending through and rotatable in the bracket arms and constituting a pivot support for the blade carriage, separate spring housings secured to each carriage arm, the housings and the carriage arms closely embracing the bracket arms, and blade counterbalancing springs in said housings.

10. In combination with an electric switch blade member, a supporting bracket member to which the blade is pivoted, one of the members having a pair of arms embracing the other member, a pair of spring housings secured to and overlying the outer sides of the arms at the axis of rotation of the blade, and blade counterbalancing springs in said housings.

11. In combination with an electric switch blade, means for pivotally supporting the blade for swinging movement, said means including a supporting bracket having a pair of arms embracing the blade, a pair of spring housings secured to the blade, the spring housings overlying the outer sides of the arms at the axis of rotation of the blade, and blade counterbalancing springs in said housings.

12. In an electric switch, a contact structure including a contact stud, a contact rod carriage pivoted to swing about an axis extending through the stud, and a plurality of contact rods mounted on the carriage and slidably engaging the stud and exerting a spring pressure thereagainst, said stud being a cam which changes the spread of the rods when the rods are in a certain position on the stud as the rods slide on the stud.

13. In an electric switch, a contact structure including a contact stud, a pivotally mounted contact rod carriage, and a plurality of contact rods mounted on the carriage and slidably engaging the stud and exerting a spring pressure thereagainst, said stud being circular in cross section with a part of the periphery thereof slabbed off to reduce the effective thickness of the stud at the slabbed off part thereof, whereby the stud constitutes a cam tending to hold the carriage in the position where the rods engage the stud at the slabbed off portion thereof.

14. In an electric switch, a contact structure including a contact stud, a contact rod carriage mounted for pivotal movement about the center of the stud as an axis, a plurality of resilient contact rods mounted on the carriage and slidably engaging the stud, and a locking cam over which one of the rods springs as it reaches one limiting position for resiliently holding the carriage in said limiting position.

15. In an electric switch, a contact structure

including a contact stud having a pair of spaced surfaces which are circular and on the same axis, a contact rod carriage having a pair of arms, said arms being journalled about said surfaces of the contact stud, and a plurality of contact rods carried by the carriage and slidably engaging the stud and exerting a spring pressure thereagainst.

16. In an electric switch, a contact structure including a contact stud having a pair of spaced surfaces which are circular and on the same axis, 10

a contact rod carriage having a pair of arms, said arms being journalled about said surfaces of the contact stud, a plurality of contact rods carried by the carriage and slidably engaging the stud and exerting a spring pressure thereagainst, at least one end rod extending beyond the stud, and a locking cam over which the last mentioned rod springs as it reaches its limiting position.

JAMES P. DUNLAP.
